United States Patent Office.

J. S. FARRINGTON, OF MILWAUKEE, WISCONSIN.

Letters Patent No. 65,556, dated June 11, 1867.

IMPROVED BED-BOTTOM.

The Schedule referred to in these Letters Patent and making part of the same.

TO ALL WHOM IT MAY CONCERN:

Be it known that I, J. S. FARRINGTON, of the city and county of Milwaukee, and State of Wisconsin, have invented a new and useful improvement in Spring-Bed Bottoms; and I do hereby declare that the following is a full, clear, and exact description thereof, which will enable those skilled in the art to make and use the same, reference being had to the accompanying drawings, forming part of this specification, in which—

Figure 1 is a side elevation view; and

Figure 2, a section.

Similar letters of reference in each of the figures indicate corresponding parts.

A, guide-rods at the corners of the bed-bottom. B, rubber forming the centre of the holes in the corners of the bottom frame, through which pass rods A. C, bell-mouth openings of the top and bottom of the holes in the bottom frame, allowing free play of rods A when thrown out of perpendicular, by means of one side or one corner of the upper frame being depressed more than other portions of said upper frame. D, pins with which to adjust rods A and hold the springs down as may be desired. E, top and bottom frame. F, springs. G, slats on which the springs stand. Across the upper frame canvas or some other textile fabric is stretched, to which the top of the springs is attached.

Operation: When one side or one corner of the top frame is pressed down by weight the guide-rods A on the weighted side pass down through the holes C, and the other side is prevented from rising up by pins D in rods A. To prevent the head of the bed sinking lower than the foot in consequence of more weight coming on that part, the foot should be pressed down lowest on the start, and held so by the pins D in rods A.

What I claim as my invention, and desire to secure by Letters Patent, is—

Top and bottom frame E, with bell-shaped openings with rubber B, guide-rods A and pins D, all combined and arranged substantially as and for the purpose described.

J. S. FARRINGTON.
